US00D954983S

(12) **United States Design Patent** (10) **Patent No.:** **US D954,983 S**
(45) **Date of Patent:** **** Jun. 14, 2022**

(54) **COVID IMMUNOASSAY TEST DEVICE**

(71) Applicant: **Hangzhou Biotest Biotech Co., LTD,**
Zhejiang (CN)

(72) Inventors: **Chunsheng Ye**, Zhejiang (CN);
Zhenxing Zhang, Zhejiang (CN);
Zhenyu Wang, Zhejiang (CN); **Luna Hou**, Zhejiang (CN)

(73) Assignee: **Hangzhou Biotest Biotech Co., LTD.,**
Hangzhou (CN)

(**) Term: **15 Years**

(21) Appl. No.: **29/749,358**

(22) Filed: **Sep. 4, 2020**

(51) LOC (13) Cl. **24-02**

(52) U.S. Cl.

USPC **D24/223**

(57) **CLAIM**

The ornamental design for a COVID immunoassay test device, as shown and described.

DESCRIPTION

FIG. 1 is a front view of a COVID immunoassay test device according to the present design;

FIG. 2 is a rear view the COVID immunoassay test device of FIG. 1;

FIG. 3 is a left view of the COVID immunoassay test device of FIG. 1;

FIG. 4 is a right view of the COVID immunoassay test device of FIG. 1;

FIG. 5 is a top view of the COVID immunoassay test device of FIG. 1;

FIG. 6 is a bottom view of the COVID immunoassay test device of FIG. 1;

FIG. 7 is a front perspective view of the COVID immunoassay test device of FIG. 1;

FIG. 8 is a rear perspective view of the COVID immunoassay test device of FIG. 1; and,

FIG. 9 is an exploded view of the COVID immunoassay test device of FIG. 1.

1 Claim, 9 Drawing Sheets
